LATCH MECHANISM

James H. McDerment, Cleveland, Ohio, assignor
to The Swartwout Company, Cleveland, Ohio,
a corporation of Ohio

Application August 21, 1935, Serial No. 37,197

11 Claims. (Cl. 98—42)

This invention relates to a ventilator of the type having a damper mounted on a parallelogram linkage and adapted to be swung to and from open and closed position by toggle linkage actuated by a bar slidable parallel to the damper and has especial reference to the provision of such a damper having a novel and effective catch mechanism cooperating therewith.

An object of the invention is to provide a simple and sturdy latch mechanism, particularly suited for the requirements of such a ventilator and to combine the same with such ventilator in a novel and effective manner.

With the foregoing and other and more limited objects in view, as will become apparent, the invention consists in all the novel features of construction of the latch mechanism and its cooperation with the remainder of the ventilator mechanism and to the novel arrangements of parts hereinafter described and illustrated in the accompanying drawings wherein Fig. 1 is a transverse section corresponding substantially to the line 1—1 of Fig. 2; Figs. 2 and 2a make up a fragmentary central vertical section with parts broken away and showing the parts in the relative positions occupied when the damper is closed; Fig. 3 is a view similar to a portion of Fig. 2 but showing the parts in an intermediate position between closed and open positions of the damper; Fig. 4 is a view similar to Fig. 3 but showing the parts in the relations occupied when the damper is open; Figs. 5 and 5a make up a fragmentary section corresponding substantially to the line 5—5 of Fig. 1; and Figs. 6 to 8 inclusive are sectional views corresponding to the lines 6—6, 7—7, and 8—8 of Figs. 2, 3, and 4 respectively.

By reference to Fig. 1, it will be seen that my improved ventilator is applicable to, for example, a building roof indicated by the numeral 10 and carrying upwardly converging sheet metal elements 11 having their upper edges secured together at intervals by bars 12 extending thereacross and riveted thereto as well as to bows 13 having lower portions lying along the elements 11 and vertically extending portions positioned adjacent the upper edges of the elements 11 and connected together by upper bight portions. The bight portion of the elements 13 merges with the legs thereof by flattened corners to which is secured a ridge roll 14. Upwardly and outwardly extending supporting bars 15 are secured to the ridge roll 14, supported by the bows 13 and provide supports for the upper edges of baffle elements 16 which are attached at their lower edges to the elements 13 in any suitable manner. As will be

clear from Fig. 1, the elements 11 terminate in vertical portions 17 upon which the outer edges of a damper 18 are adapted to rest. Secured to the damper 18 and extending thereacross at intervals are straps 19 to the ends of which are pivotally connected links 20. The upper ends of the links 20 are pivoted to the bows 13, as indicated at 21. Disposed beneath the damper 18 and held in position by suitable guides 22 is a slidably mounted bar 23 to which is pivotally connected at 24 a link 25 in turn pivoted at 26 to the damper 18. It will be obvious that when the bar 23 is reciprocated, motion will be transmitted through the link 25 to the damper 18 with the result that the same will be swung on its parallelogram linkage.

Any suitable mechanism may be provided for reciprocating the bar 23. In the drawings, I have shown one suitable mechanism for the purpose which comprises a bracket 27 connected to the bar 23 and carrying a sheave 28 over which passes a flexible element 29 secured at 30 to an element 31 mounted on transverse members 12 and 32 and carrying a second sheave 33 over which the flexible element 29 passes downward to a suitably convenient operating point.

Pivoted to one of the guides 22 which is mounted on one of the transverse members 12 is a holding member 34 comprising a pair of triangular elements spaced from each other by posts or pins 35 and 36 at the free side and by pins 37 passing through spacing sleeves 38 and secured in any suitable manner to the guide member 22. The pins 37 may take the form of a single pin passing entirely through the guide member 22, in which case a slot must be provided in the bar 23. The portions 35 and 36 are adapted to engage the upper and lower surfaces of the bar 23 to limit pivotal motion of the holding member 34 transversely of the bar 23. Pivoted to the bar 23 at the point 38 is a dog 39 having a notch 40 receiving a stop 41 carried by the bar 23 and limiting the downward motion of the dog 39 to the position shown in Fig. 2 while permitting an upward motion thereof about sufficient to elevate the lower end of the cam face 42 to the top of the cut-out 43 in the bar 23. Pivoted to the bar 23 in a position not to interfere with the dog 39, for example, on the other side of the bar 23, is a shifting member 44, such shifting member being pivoted to the bar 23 at 45 and having its counterclockwise motion with respect to the bar 23 limited by a stop 46. The shifting member 44 is provided with a notch 47 which is held by the pin 48 in position to engage the portion 35 of the

holding member 34 upon motion of the bar 23 toward the left.

The operation of the catch mechanism may be readily understood by reference to Figs. 2 to 4 inclusive. When the damper 18 is in closed position, the parts of the catch mechanism occupy, under the influence of gravity, the positions indicated in Figs. 2 and 2a. It is to be understood that this mechanism is capable of use in other than a horizontal position by substituting suitable springs or equivalent means for the forces due to gravity in the arrangement illustrated. Upon exerting a downward force on the cable 29, the bar 23 will move toward the left until the portion 35 is received in the notch 41. Upon further motion, the notch 41 being above the pivot point 45, and the portion 35 being above the pivot point 37, the parts 39 and 44 are, so to speak, buckled to the position indicated in Fig. 3. As the element 34 is moving counterclockwise about the pivot point 37, the portion 36 will move upwardly into the cut-out 43, the dog 39 pivoting upwardly when the element 36 engages its lower surface until when the bar 23 is moved to the position in Fig. 3, the lower end of the cam face 42 of the dog 39 will have passed rearwardly of the portion 36 and dropped down to the position of Fig. 3.

When the parts have reached the position of Fig. 3, the bar 23 will be allowed to move toward the right with the result that the pivot point 45 will move slightly "out from under" the portion 35, thereby lowering the portion 36 to some extent but not to a point below the dog 39. As soon as the cam face 42 of the dog engages the element 36, it will impart an upward motion to the holding member 34 thereby allowing the shifting member 44 to be withdrawn from engagement with the portion 35 and to drop by gravity into the position of Fig. 4, in which position it will hold the damper open, that is, it will prevent further motion of the bar 23 to the right.

When it is desired to close the damper, a downward force is exerted on the flexible cable 29 with the result that the bar 23 is moved toward the left. A very small motion to the left will move the dog 39 out of engagement with the portion 36 and allow the holding member 34 to drop down until the portion 35 engages the upper surface of the bar 23 or the upper surface of the shifting member 44 if the same should have such configuration as to extend above the upper surface of the bar at that point. Upon release of the cable 29, the parts will be free to move under the influence of gravity to the position of Figs. 2 and 2a.

While I have shown and described the preferred embodiment of my invention, I wish it understood that I am not limited to the details of the disclosure but only in accordance with the appended claims and the prior art.

Having thus described my invention, what I claim is:

1. A catch mechanism for holding a bar in longitudinally adjusted position comprising, a support in operative relation to which said bar is longitudinally movable, a holding member secured to said support and movable relative thereto and laterally of said bar, a dog carried by and movable with respect to said bar for engaging a portion of said holding member to arrest motion of said bar in one direction, a shifting member movably carried by said bar and means including said shifting member acting, upon longitudinal motion of said bar in the other direction, to

move a portion of said holding member into a position to be engaged behind said dog upon reversing the motion of said bar.

2. A catch mechanism for holding a bar in longitudinally adjusted position comprising, a support in operative relation to which said bar is longitudinally movable, a holding member movably secured to said support and having portions embracing said bar and movable laterally thereof, a dog carried by and movable with respect to said bar for engaging one of said portions to arrest motion of said bar in one direction, a shifting member carried by said bar for engaging the other of said portions to move said holding member, upon longitudinal motion of said bar in the other direction, into position to be engaged by said dog upon reversing the motion of said bar.

3. A catch mechanism for holding a bar in longitudinally adjusted position comprising, a support in operative relation to which said bar is longitudinally movable, a holding member secured to said support and movable relative thereto and laterally of said bar, a dog carried by and movable with respect to said bar for engaging a portion of said holding member to arrest motion in one direction, a shifting member movably carried by said bar and means including said shifting member acting, upon longitudinal motion of said bar in the other direction, to move a portion of said holding member into a position to be engaged behind said dog upon reversing the motion of said bar, and means including a cam surface on said dog for disengaging said shifting member from said holding member upon such reverse motion.

4. A catch mechanism for holding a bar in longitudinally adjusted position comprising, a support in operative relation to which said bar is longitudinally movable, a holding member movably secured to said support and having portions embracing said bar and movable laterally thereof, a dog carried by and movable with respect to said bar for engaging one of said portions to arrest motion of said bar in one direction, a shifting member carried by said bar for engaging the other of said portions to move said holding member, upon longitudinal motion of said bar in the other direction, into position to be engaged by said dog upon reversing the motion of said bar, and means including a cam surface on said dog for disengaging said shifting member from said holding member upon such reverse motion.

5. A catch mechanism for holding a bar in longitudinally adjusted position comprising, a support in operative relation to which said bar is slidably, a holding member movably secured to said support and having upper and lower portions embracing said bar and movable laterally thereof, a dog carried by and movable with respect to said bar for engaging one of said portions to arrest motion of said bar in one direction, a shifting member pivoted to said bar at a point below the lowermost position of the upper of said portions and having a notch and means for presenting the same at a position to engage said upper portion upon longitudinal motion of the shifting member toward said holding member.

6. A catch mechanism for holding a bar in longitudinally adjusted position comprising, a support in operative relation to which said bar is slidably, a holding member movably secured to said support and having upper and lower por-

tions embracing said bar and movable laterally thereof, a dog carried by and movable with respect to said bar for engaging one of said portions to arrest motion of said bar in one direction, a shifting member pivoted to said bar at a point below the lowermost position of the upper of said portions and having a notch and means for presenting the same at a position to engage said upper portion upon longitudinal motion of the shifting member toward said holding member, means limiting the movement of said dog in one direction, said dog being provided with a cam surface for engaging the lower of said portions to release said shifting member as said dog arrests the motion of said bar.

7. In a ventilator construction, in combination with means defining an opening, a damper adapted to close said opening, a support, a parallelogram linkage connecting said damper to said support, a bar mounted for slidable motion with respect to said support, a link pivoted to said bar and to said damper, a holding member secured to said support and movable relative thereto and laterally of said bar, a dog carried by and movable with respect to said bar for engaging a portion of said holding member to arrest motion of said bar in one direction, a shifting member movably carried by said bar and means including said shifting member acting, upon longitudinal motion of said bar in the other direction, to move a portion of said holding member into a position to be engaged behind said dog upon reversing the motion of said bar.

8. In a ventilator construction, in combination with means defining an opening, a damper adapted to close said opening, a support, a parallelogram linkage connecting said damper to said support, a bar mounted for slidable motion with respect to said support, a link pivoted to said bar and to said damper, a holding member movably secured to said support and having portions embracing said bar and movable laterally thereof, a dog carried by and movable with respect to said bar for engaging one of said portions to arrest motion of said bar in one direction, a shifting member carried by said bar for engaging the other of said portions to move said holding member, upon longitudinal motion of said bar in the other direction, into position to be engaged by said dog upon reversing the motion of said bar.

9. In a ventilator construction, in combination with means defining an opening, a damper adapted to close said opening, a support, a parallelogram linkage connecting said damper to said support, a bar mounted for slidable motion with respect to said support, a link pivoted to said bar and to said damper, a holding member mov-

ably secured to said support and having portions embracing said bar and movable laterally thereof, a dog carried by and movable with respect to said bar for engaging one of said portions to arrest motion of said bar in one direction, a shifting member carried by said bar for engaging the other of said portions to move said holding member, upon longitudinal motion of said bar in the other direction, into position to be engaged by said dog upon reversing the motion of said bar, and means including a cam surface on said dog for disengaging said shifting member from said holding member upon such reverse motion.

10. In a ventilator construction, in combination with means defining an opening, a damper adapted to close said opening, a support, a parallelogram linkage connecting said damper to said support, a bar mounted for slidable motion with respect to said support, a link pivoted to said bar and to said damper, a holding member movably secured to said support and having upper and lower portions embracing said bar and movable laterally thereof, a dog carried by and movable with respect to said bar for engaging one of said portions to arrest motion of said bar in one direction, a shifting member pivoted to said bar at a point below the lowermost position of the upper of said portions and having a notch and means for presenting the same at a position to engage said upper portion upon longitudinal motion of the shifting member toward said holding member.

11. In a ventilator construction, in combination with means defining an opening, a damper adapted to close said opening, a support, a parallelogram linkage connecting said damper to said support, a bar mounted for slidable motion with respect to said support, a link pivoted to said bar and to said damper, a holding member secured to said support and having upper and lower portions embracing said bar and movable laterally thereof, a dog carried by and movable with respect to said bar for engaging one of said portions to arrest motion of said bar in one direction, a shifting member pivoted to said bar at a point below the lowermost position of the upper of said portions and having a notch and means for presenting the same at a position to engage said upper portion upon longitudinal motion of the shifting member toward said holding member, means limiting the movement of said dog in one direction, said dog being provided with a cam surface for engaging the lower of said portions to release said shifting member as said dog arrests the motion of said bar.

JAMES H. McDERMINT.
